UNITED STATES PATENT OFFICE

ALBERT E. REPENNING, OF OAK PARK, ILLINOIS, ASSIGNOR TO ORANGE-CRUSH COMPANY, OF CHICAGO, ILLINOIS

DESIGN FOR A DISPENSER DISPLAY STAND

Application filed October 21, 1929. Serial No. 33,124. Term of patent 14 years.

To all whom it may concern:

Be it known that I, ALBERT E. REPENNING, a citizen of the United States, residing at Oak Park, Illinois, have invented a new, original, and ornamental Design for Dispenser Display Stand, of which the following is a specification, reference being had to the accompanying drawing, forming a part thereof.

The figure is a perspective view of the dispenser display stand.

I claim:

The ornamental design for a dispenser display stand, as shown.

A. E. REPENNING.
